RENÉ ACHILLE ROBIN, OF PARIS, FRANCE.

KINEMATOGRAPHIC APPARATUS FOR TAKING AND PROJECTING VIEWS BY MEANS OF PHOTOGRAPHIC PLATES.

1,079,187.

Specification of Letters Patent. Patented Nov. 18, 1913.

Application filed August 9, 1909. Serial No. 511,956.

To all whom it may concern:

Be it known that I, RENÉ ACHILLE ROBIN, a citizen of the Republic of France, and a resident of Paris, France, have invented 5 new and useful Improvements in Kinematographic Apparatus for Taking and Projecting Views by Means of Photographic Plates, which is fully set forth in the following specification.

10 This invention has for its object an improvement in kinematographic apparatus, wherein pictures are projected upon a screen in such rapid succession that the effect of movement is obtained, and wherein means 15 is provided for projecting pictures on ordinary glass plates instead of films.

A further object of the invention is to provide means for compensating for the frequent irregularities in the height, width and 20 thickness of the plates.

In the drawings: Figure 1 is a general front elevation of the apparatus, with the wall of the box which constitutes the dark chamber inclosing the apparatus in section, 25 Fig. 2 is an end view with the box in section, Fig. 3 is a horizontal section on the line 3—3 of Fig. 2, Fig. 4 is an enlarged detail sectional view of a portion of Fig. 1, Fig. 5 is a front view of a plate showing the 30 frame, Figs. 6, 7 and 8 are diagrammatic views showing a portion of the escapement for producing the alternations of movement and stoppage of the magazine carriage. Fig. 9 is a detail sectional view 35 of a shutter with two sets of exposure apertures for taking and projecting pictures, Fig. 10 is a diagrammatic view of a modification of mechanism for utilizing the force exerted by a plate passing from the vertical 40 carrier to the receiving magazine to cause the ejection of a plate from the distributing magazine and to cause the said plate to engage the vertical carrier, Fig. 11 is an end view of a modified form of construction.

45 It will be understood that the improved apparatus is designed to project pictures from plates, wherein the pictures are arranged in a plurality of horizontal rows on the plate, each plate having a large number 50 of pictures. Each plate is lifted to bring the first picture of the upper row in front of the objective, and the plate is moved laterally to bring each of the pictures in the row opposite the objective in succession and with a positive stop for each pic-

ture of the row. The plate is again lifted to bring the second row to the level of the objective and the movement of the plate is reversed, to bring the pictures of the second row opposite the objective in succession, but in the reverse direction to the movement of the plate in exposing the pictures of the first row.

60 The present embodiment of the invention comprises broadly the following mechanisms, namely; a distributing or supplying magazine, a receiving magazine, and a carriage for moving the plates transversely, a conveyer for moving the plates vertically, the objective for projecting the pictures, and a 70 cylindrical cam for operating the carriage and the conveyer.

75 The apparatus is inclosed in a box *a*, of suitable material, and the carriage *b* is formed by a pair of laterally spaced cheek plates *b'* and two separate and independent compartments *b²* and *b³* are arranged between the cheek plates. The compartment *b²* is the supplying or distributing magazine for the plates to be exposed or projected, 80 while a compartment *b³* is the receiving magazine for receiving the plates after they have been exposed. The objective *e* is arranged between the magazines, and at approximately the center of the front of the box, the said front being closed by a plate *a^x* through which the outer end of the objective extends, as shown more particularly in Figs. 2 and 3. The plates to be exposed are passed 85 in succession from the compartment *b²* to the compartment *b³* and each picture of each plate is stopped momentarily before the objective *e*. The carriage *b* is supported by a shaft or bar *a'*, whose ends are fixed to the walls of the box *a*, and the said carriage is journaled on the shaft or bar, by means of sectional bearings *b⁷*, *b⁸*, each of the said bearings being secured on the shaft or bar by means of a bolt *b^x*. A roller *b⁶* is journaled at the top of the carriage, and the said roller engages the channel by a U-shaped track *a²*, secured to the inner face of the top of the box, as shown in Figs. 1 and 2.

90 The cam *c* that operates the carriage is arranged in front of the carriage, and the box front *a^x* is provided with an arc-shaped extension *a^o* for receiving the said cam. The cam is operated by means of a crank *d* outside the box, and rigid with a pinion or gear wheel *d'* inside the box which meshes 95 100 105 110

with a gear wheel d^2 on the cam. The pinion d' also meshes with a pinion i^2 , secured on the shaft i' of the rotary shutter i . The handle d thus operates simultaneously the 5 cam c , and the rotary shutter i .

The carriage b is provided with a roller h , and the said roller engages a helicoidal groove in the cam c . The rotation of the cam c constrains the carriage to move laterally, in order to pass a picture before the objective, and during the moment of exposure, which coincides with the opening of the shutter, the carriage must be stopped. This stoppage is brought about by mechanism to be 10 later described.

Each of the plates to be shown is provided with a frame, consisting of a light plate f , of aluminum for instance, having a groove f^2 in one edge, for receiving one edge of 20 the plate. The gelatined face of the plate rests against one wall of the groove, and leaf springs f^3 are arranged in the groove near the ends thereof, for engaging the opposite face of the plate, to press the gelatined face against the said first named wall. Each frame is provided with an aperture f' , in the wall remote from the leaf spring, for engagement by one of the lugs of the conveyer device to be hereafter described. The plates, each provided with a frame f , are introduced one after the other into the lower compartment of the distributing magazine b^2 of the carriage b , care being taken that all of the frames f are at 30 the same side and that the sensitized faces of the plates are turned toward the objective. The plate nearest the objective, or nearest the front of the box, is pressed against a band b^4 rigid with the wall of the 40 box, and of a width corresponding to the width of the frame of a plate. All of the plates in the distributing magazine b^2 are pressed rigidly against the wall of the box by means of a plate spring f^0 , which engages that edge of the plate remote from the 45 frame f . Throughout its entire vertical displacement, each plate is engaged by rollers f^5 , f^6 and f^8 , arranged in succession, each roller being journaled at the free end of a 50 plate spring, in such manner that the roller may yield. In its vertical travel, the plate is held in the focus of the objective by its frame f , the said frame moving between the walls b^4 and b^5 (Fig. 4). At the side opposite to the frame, the plate is held in the focus of the objective, that is to say against the strip or band f^4 , by means of a roller f^6 arranged at the level of the objective. 55

A bar or beam consisting of the oppositely 60 extending arms j and j' is pivoted at j^2 upon one of the walls b' of the carriage b , and the said arms are adapted to engage the rearmost plate of each magazine. The angle of the arms j and j' of the bar with respect 65 to each other, depends upon the number of

plates employed, and the said arms are so arranged that when a plate is moved from the magazine b^2 to the magazine b^3 , the said arms will still engage the rearmost plate in each magazine, that is the arm j will be 70 moved rearwardly a distance corresponding to the thickness of one plate at the same time the arm j will be moved forwardly the same distance. The upper arm j' is extended, as shown at j^3 beyond the pivotal 75 connection j^2 of the arms, and the said extension j^3 is provided with an arc-shaped slot j^4 , formed upon a circle whose center is the pivotal connection or shaft j^2 . A threaded stem on the lower arm j passes 80 through the slot, and the said stem is engaged by a nut on the opposite side of the arm j' from the arm j . It will be evident that when the nut is loosened, the angle of the arms j j' may be changed, and the said 85 arms may be secured in adjusted position by tightening the nut to clamp the extension to the arm j . After the plates to be exposed have been placed in the magazine b^2 , a single plate is placed in the magazine b^3 , 90 the nut is loosened, and both arms are pressed against the rearmost plate, after which the nut is tightened to hold the arms in their adjusted position. A leaf spring j^5 is arranged at the end of the upper arm j' 95 for engaging the plate in the upper magazine.

The vertical conveyer for the plates is an endless chain or band g provided at spaced intervals with lugs g' , the said belt or band being supported by sprocket wheels g^2 and g^3 . These sprocket wheels are keyed to shafts which are journaled in extensions from the walls b' of the carriage b , and the run of the chain or belt that moves the 105 plates is guided in its vertical movement between the wall b^4 and a band b^6 arranged in front of the said run of the chain or band. The said band b^6 also prevents displacement of the lugs g' from the plate. 110 Upon the shaft of the wheel g^3 two escape- 115 ment wheels are secured, and one of the said wheels g^4 is arranged in the plane of the cam wheel c . The said wheel c is provided with two teeth c' and c^2 arranged diametri- 120 cally opposite on the periphery of the cam, and the said teeth are adapted to engage the teeth of the ratchet wheel g^4 . A tooth c' or c^2 will engage a tooth of the ratchet wheel g^4 twice during each rotation of the cam 125 wheel c and will move the ratchet wheel g^4 the distance of a single tooth of the said wheel. Each of the said teeth c' , c^2 ends in a nose c^5 which at the end of the movement of the ratchet wheel g^4 , that is to say at that 130 movement at which the tooth c' or c^2 is about to move out of engagement with the tooth of the ratchet wheel, will engage the succeeding tooth of the ratchet wheel, and will stop or check the movement of the ratchet

wheel at that time. The wheels c and g^4 are so proportioned that the movement imparted to the wheel g^4 by a tooth c' or c^2 will move the chain or band g a distance sufficient to lift a plate the distance between one row of pictures and the succeeding row. On account of the variations in height of the plates, it is necessary to provide some means that will insure that the central portion of each picture will be in the focus of the objective. For this reason one of the teeth G of the wheel g^4 is of greater length than the remaining teeth, and this tooth is so arranged that it will be engaged by one of the teeth c' or c^2 at the time when the plate is first moved in front of the objective. That is, this tooth D will be engaged to move the chain or band when the last picture of the last row has been shown, and the first picture of the first row of the succeeding plate is to be brought before the objective. Since the chain or band g is moved a little farther at this time, the total movement of the next plate will be slightly greater for the first row of pictures than for any of the succeeding rows. Each of the plates (Fig. 5) is provided with a plain margin, x , x' , x^2 , and this margin is variable as shown. The large tooth g is for the purpose of moving the chain or band a sufficient distance to compensate for this unexposed margin. A second ratchet wheel g^6 is arranged adjacent to the wheel g^4 on the shaft of the said wheel g^3 and a pawl in the shape of a leaf spring g^5 engages the teeth of the wheel, the said pawl acting as a retaining pawl to prevent reverse movement of the wheel g^4 . Upon the shaft of the sprocket wheel g^2 two leaf springs g^7 and g^8 are arranged, the said springs being near the ends of the shaft. The said springs press upon the plate that has been exposed, and cause it to enter the receiving magazine b^3 , that is the said springs press the plate away from the chain rearwardly into the magazine.

The shutter is rotatable, and comprises a cylinder i having two series of slots I and I'. The cylinder i is rigidly secured to a shaft i' , and the said shaft extends outside of the box a , and the said shaft is capable of longitudinal displacement, in order to bring either of the series of slots I or I' opposite the objective. The series I' is for the projection of pictures, while the series I is for taking pictures. The shaft i' is mounted to slide in a sectional sleeve or bushing i^7 , and the pinion i^8 is keyed to the shaft by a key i^9 , the said pinion being arranged between the sections of the sleeve or bushing i^7 . The shaft i' extends outside of the case a , as shown in Fig. 9, and is provided with a milled head or knob i^8 , for convenience in manipulating the shaft and the shutter. The shaft is also provided with two spaced annular grooves i^9 , which are adapted to be

engaged by a latch plate or stop i^3 connected to the case a by means of a screw i^4 . When the latch i^3 is moved out of engagement with the grooves i^9 the shaft may be moved longitudinally to bring the series I 70 or I' of slots opposite the objective. The shaft may be rotated freely when the latch plate is engaged with either groove i^9 .

The other mechanism for providing for the transverse displacement of the plates 75 and for their stoppage before the objective is as follows: The escapement lever k , k' is pivoted at k^2 to the carriage, and each of the arms k , k' of the said escapement lever is in engagement with a species of racks. The 80 arm k engages the rack l while the arm k' engages the rack l' and the said racks are arranged alongside each other, the rack l' in the rear of the rack l , and the arm k' is offset rearwardly in order that it will engage the said rack, as shown more particularly in Fig. 2. The racks l and l' are provided with teeth, each of which is composed of two planes, one plane w which is concentric with the axis of the arm k , and upon which the end x of the arm slides inoperatively, and of a plane y upon the face z of the said arm x ; the curve of the face z of the arm k is the resultant of the oscillation of the arm and of the displacement of the 90 shaft k^2 , while passing for example from the position 1 in Fig. 6 to the position 2 in Fig. 7, the distance between the points 1 and 2 being equal to the displacement of the plate in front of the objective, that is to say 100 being equal to the width of a picture. The racks l and l' are oppositely arranged, that is the rack l bears the same relation to the arm k that the rack l' bears to the arm k' . The faces of the teeth of the rack l' are 105 designated by the reference characters w' and y' , while the end of the arm k' is designated by the reference character x' , and the inner face of the arm by the reference character z' . From this arrangement, it results 110 that when the arms k and k' occupy the position of Fig. 6, the carriage has reached the end of its movement in the direction of the arrow X, and at this moment, the roller h is engaged in the concentric portion of the 115 groove of the cam e . At this moment the roller and the carriage is locked from movement, by the slight engagement of the face x' of the arm k' upon the face w' of a tooth of the rack l' (Fig. 6). Immediately that the cam e displaces the roller h in the direction indicated by the arrow Y, the roller leaves the concentric portion e^6 in the cam, and the shaft k^2 and the carriage b is displaced laterally, the arm k , k' occupying the 120 position 2 of Fig. 7. As soon as the roller h leaves the concentric portion of the cam it is displaced in the opposite direction, that is, in the direction of the arrow Y, and the arms k , k' engage the faces w , w' of the 125 cam e . The carriage is stopped by the 130

teeth of the racks l , l' . These faces of the teeth are, however, concentric with the axis upon which the arms swing, and the said arms can rock without displacing the shaft 5 k^2 and the carriage. This period of stoppage corresponds to the exposure for projecting or taking second picture, and the stoppage ceases when the arms k , k' reach the position 3 of Fig. 8. At this moment, 10 the arms k , k' occupy a position similar to that shown in Fig. 6, except that the carriage has been displaced by one horizontal division of the plate, and the same position, that is from position 1 to position 3 are repeated, for exposing a new plate and for 15 again advancing the carriage. It will be noted, that the roller h is displaced by the cam c in a uniform and continuous manner, and that the shaft k^2 and the carriage b , is 20 locked during the oscillation of the arms, in passing from the position 2 of Fig. 7 to the position 3 of Fig. 8. The shaft k^2 and the carriage b advance during the oscillation of the arms k , k' from the position 1 of Fig. 6 25 to the position 2 of Fig. 8, by a length equal to the total advance of the roller h in passing from the position 1 of Fig. 6 to the position 3 of Fig. 8. The three corresponding 30 positions of the arms k , k' on the return of the carriage in the direction X are represented in dotted lines in Figs. 6 and 8, their action being the reverse of that shown in full line. The two ends of the groove at the 35 point where it alters its direction are connected by concentric portions c^6 , and which correspond with the moments at which the plate is displaced vertically, in order to pass from one horizontal row to another. The concentric development of these portions of 40 the groove is such that time is permitted for exposing the last rectangle of the row which is finished, time for the screening of the objective during the rise of the plate to expose the succeeding row, and time for 45 exposing the first picture of the succeeding row.

The device operates as follows:—Any desired number of plates x are arranged in the distributing magazine b^2 , each plate being 50 connected with its frame f . The arms j , j' are adjusted to press the plates in the magazines firmly toward the conveyer. Should for instance it be desired to take pictures, the handle d is rotated, and the first lug g 55 that presents itself in front of the base of the magazine b^2 engages in the opening f' of the frame f of the first plate in the magazine. The plate is lifted to bring the first row of pictures to the level of the objective, and 60 as the said plate moves, it meets one of the small rollers f^5 which presses it to the bottom of the frame and causes the frame to slide against the wall b' of the carriage. The difference in width of the plates will be on 65 the opposite side from the frame, and the

plates will be in alinement so far as their edges are concerned at the side adjacent to the frame. The plate is then engaged by the roller f^6 (Fig. 4) and the said roller holds the plate in the focus of the objective 70 and assists the arm j to hold the plate firmly against the wall b' , while the roller g^7 presses the plate laterally together with its frame against the wall b' . When the plate is lifted to bring the first picture of the first row 75 opposite the objective, the tooth c' or c^2 of the cam engages the tooth G of the ratchet wheel g^3 and since this tooth is slightly longer than the remaining teeth, the plate is lifted upwardly a slightly greater distance 80 than the vertical length of a picture. This additional lift corresponds to the aggregate width of the magazines, at the top and the bottom of the plate. The carriage is displaced laterally, and stopped positively for 85 an instant when each picture is directly opposite the objective by the cam c and the escapement mechanism, the displacement of the carriage taking place always at the movement when the objective is screened. 90 The objective is uncovered or unscreened for exposing the plate while the carriage is stationary. When the carriage reaches the end of its lateral travel in one direction, the roller h engages the concentric portion c^6 of 95 the groove, and during the time that the roller is engaged with this portion of the groove, the other tooth c' or c^2 acts upon the ratchet wheel g^3 to move the said wheel the distance of one tooth whereby to cause the 100 plate to ascend and present a fresh row of pictures at the level of the objective, after which the carriage is displaced laterally in the opposite direction. When the first plate passes above the level of the magazine b^2 , 105 the second plate in the said magazine is pressed forward by the arm j , the said arm j being actuated by the reaction of the spring j^3 connected to the arm j' . The said first plate at this time is still opposite the objective, and the second plate in the magazine b^2 is pressed against the wall b^4 and follows directly after the first plate. As soon as a lug g' on the chain 110 g^2 enters the opening f' in the frame f of the said second plate, the said plate will be displaced vertically at the next movement of the chain. When the first plate reaches the level of the magazine b^3 , an inclined plane b^{13} causes the upper end of the plate 115 to enter the magazine, and at the same time the springs g^7 and g^8 pressing upon the frame f and the opposite edge of the plate force the said plate into the magazine, compressing the spring g^3 of the arm j' and 120 causing the arm j to press the plates in the lower magazine toward the chain g . It will be understood that when the plates have thus been exposed, a corresponding number 125 of positives are made from the negatives, 130

and when the positives are passed through the apparatus in the same direction as the plates of the negatives were passed, the pictures will be projected upon a screen or the like in such rapid succession that the effect of motion will be gained.

Although the apparatus is more particularly designed and constructed for taking or projecting successive rows of pictures on plates, it will be understood that the same principle may be employed for exposing successive pictures on films or for exposing pictures on films in continuous bands. In Fig. 11, a modified form is shown for this purpose. In this embodiment of the invention, the distributing magazine is replaced by a reel or bobbin v , the said bobbin or reel being mounted on the carriage b and from the reel or bobbin v the strip passes and winds upon a reel or bobbin v' which takes the plate of the magazine b^3 . A continuous strip or film is used, and the ratchet wheel g^4 differs from the ratchet g^4 of Fig. 2 by the omission of the tooth G . The film strip is moved laterally by the carriage b in the same manner as the plates are moved to project the successive pictures of a row and the film is moved vertically to bring the successive rows before the objective by means of the wheels g^2 , g^3 engaging the perforations of the film. In other words the apparatus is precisely the same, except that instead of magazines for plates, reels or bobbins are provided upon which the film may be wound. The movement of the film is brought about by the teeth of the wheels g^2 and g^3 , the said teeth engaging the perforations of the strip, and the chain is not provided with lugs since it serves only to transmit movement of the wheel g^2 to the wheel g^3 .

The shaft i' of the shutter i may be moved longitudinally to bring either series of slots I or I' opposite the objective, by means of a milled head or knob i^8 secured to the outer end of the shaft i' , and the said shaft is provided with two longitudinally spaced annular grooves i^9 for engagement by a lug i^3 pivoted to the wall of the box a by means of a screw i^4 . The shaft i' is journaled in a sleeve i^7 , and the pinion or gear wheel i^2 is keyed to the shaft by a key or feather i^6 .

It will be noted from an inspection of Figs. 1, 2 and 11, that mechanism is provided for absorbing the shock of the stoppage of the carriage, when the said carriage is stopped to permit a picture to be taken or projected. For this purpose a lever k^3 is provided rigid with the escapement lever k k' . The said lever is forked at its lower end, and the arms k^4 of the fork extend on opposite sides of a plate spring k^5 secured to one of the cheek plates b' . The plate spring k^5 is so arranged, that whenever the escapement

k k' is rocked, one of the arms of the fork k^3 will engage the plate spring, to cushion the stoppage of the carriage.

I claim—

1. In a device of the character specified, means for transporting the plate carriage transversely of the objective, comprising in combination with the carriage, a rotatable cylindrical cam provided with a plurality of helicoidal grooves running in opposite directions, and connected at each end by circular grooves concentric with the axis of rotation of the cam, and means for imparting intermittent movement to the carriage, said means comprising an anchor escapement rocking upon the carriage, a plurality of racks arranged adjacent to the escapement, each arm of the escapement engaging a rack, and a roller carried by the escapement and engaging the grooves of the cam.

2. In a device of the character specified, the combination with a carriage and the cam having helicoidal grooves, of an escapement lever mounted to rock on the carriage, a roller on the lever engaging the grooves, and a plurality of oppositely arranged racks having teeth engaged by the arms of the escapement lever, the teeth of the rack having one face curved to correspond with the curve of the arms of the escapement lever, and the other face plane, whereby the carriage will remain stationary during one oscillation of the escapement lever produced by a displacement of the roller by the groove, and will be advanced during the other oscillation.

3. In a device of the character specified, the combination with the carriage and the cam having helicoidal grooves, of an escapement lever mounted for oscillation on the carriage, a roller connected to the lever and engaging the grooves for swinging said lever, and a rack engaged by each arm, said racks being oppositely arranged, the teeth of the racks each having one face curved to correspond with the curve of the arm and the other plane, whereby the carriage will be advanced during the oscillation of the lever in one direction, and will be held stationary during the oscillation of the lever in the other direction.

4. In a device of the character specified, the combination with the carriage and the rotating cam having helicoidal grooves, of a roller on the carriage engaging the grooves for moving the carriage, and means in connection with the cam and roller for holding said carriage stationary at predetermined periods, said means comprising an escapement lever mounted to rock on the carriage and on which the roller is journaled, and a pair of oppositely arranged racks for engagement by the respective arms of the escapement lever, one face of each tooth of the racks being plane and the other curved, the

- 6
- arms being similarly curved, whereby the carriage will remain stationary during the oscillation of the lever in one direction and will be advanced during its oscillation in the other direction.
5. In a device of the character specified, the combination with the carriage and the rotating cam having helicoidal grooves, of a roller on the carriage engaging the grooves 10 for moving the carriage, and means in connection with the cam and the roller for holding said carriage stationary at predetermined periods.
15. In a device of the character specified, comprising a carriage for supporting the plates, and an endless conveyer for lifting the individual plates, of means for operating the conveyer comprising escapement wheels connected therewith, and means engaging the teeth of the wheels for intermittently rotating the said wheels, sundry of said teeth being of greater length than the remaining teeth for compensating for variations in height of the plates.
20. In a device of the character specified, a carriage for supporting the plates, an endless conveyer having lugs for engaging and moving the individual plates vertically, and means for guiding the plates during their 25 vertical movement, said means comprising a frame for each plate consisting of a strip having a groove for engagement by the edge of the plate, springs for holding the plates in focus, said strips having openings for 30 the passage of the lugs, and spring controlled rollers engaging the plates laterally and longitudinally for the purpose specified.
35. In a device of the character specified, a carriage for supporting the plates, an endless conveyer having lugs for engaging and moving the individual plates vertically, and means for guiding the plates during their 40 vertical movement.
45. In a device of the character specified, a plurality of magazines, and means for feeding the plates from one magazine to the other, said means comprising a beam having arms, and means whereby the angle of the arms with respect to each other may be 50 varied, said arms engaging the plates, an inclined stop on the receiving magazine for engagement by the edge of the plate to deflect said plate, and springs pressing said arms to force the plate toward the stop.
55. In a device of the character specified, the combination with the carriage, the cam for operating the carriage, and the escapement lever on the carriage and having means for engaging the cam to move the carriage, 60 and means for intermittently checking the movement of the carriage, said means comprising an escapement lever mounted to rock on the carriage, and a pair of oppositely arranged racks for engagement by the respective arms of the escapement lever, of a 65 shock absorber for cushioning the stoppage of the carriage, said absorber comprising a lever rigid with the said escapement lever and rocking therewith, and a spring on the carriage for engagement by the lever at the 70 end of its movement in each direction.
75. In a device of the character specified, the combination with the carriage, and the means for moving the carriage laterally with alternate periods of movement and rest, of means for supporting and guiding the carriage, said means comprising a rod upon which the carriage slides, collars adjustable on the rod on opposite sides of the carriage, a roller on the carriage, and a track for engagement by the roller.
80. In a device of the character specified, comprising an objective, a shaft, a carriage arranged transversely of the shaft and having a distributing magazine below the shaft and a receiving magazine above the shaft and mounted to slide laterally upon the shaft, means for moving the said carriage laterally past the objective in opposite directions from end to end of the shaft, means for holding the carriage stationary at predetermined intervals, and means movable with the carriage for engaging the plates in the lower magazine and for moving them from the lower magazine to the upper magazine 85 with alternate periods of motion and rest.
85. In a device of the character specified, comprising an objective, a carriage having a lower distributing magazine for plates, and an upper receiving magazine for plates, means for moving the carriage laterally past the objective in opposite directions, means for holding the carriage stationary at predetermined intervals, means movable with the carriage for engaging the plates in the lower magazine and for moving them from the lower magazine to the upper magazine 90 with alternate periods of motion and rest.
95. In a device of the character specified, comprising an objective, a carriage having a lower distributing magazine for plates, and an upper receiving magazine for plates, means for moving the carriage laterally past the objective in opposite directions, means for holding the carriage stationary at predetermined intervals, means movable with the carriage for engaging the plates in the lower magazine and for moving them from the lower magazine to the upper magazine 100 with alternate periods of motion and rest.
100. In a device of the character specified, comprising an objective, a carriage having a lower distributing magazine for plates, and an upper receiving magazine for plates, means for moving the carriage laterally past the objective in opposite directions, means for holding the carriage stationary at predetermined intervals, means movable with the carriage for engaging the plates in the lower magazine and for moving them from the lower magazine to the upper magazine 105 with alternate periods of motion and rest.
110. In a device of the character specified, comprising an objective, a carriage having a lower distributing magazine for plates and an upper receiving magazine for plates, means for moving the carriage laterally past the objective in opposite directions, means for holding the carriage stationary at predetermined intervals, means movable with the carriage for engaging the plates in the lower magazine, and for moving them from the lower magazine to the upper magazine 115 with alternate periods of motion and rest.
120. In a device of the character specified, comprising an objective, a carriage having a lower distributing magazine for plates and an upper receiving magazine for plates, means for moving the carriage laterally past the objective in opposite directions, means for holding the carriage stationary at predetermined intervals, means movable with the carriage for engaging the plates in the lower magazine, and for moving them from the lower magazine to the upper magazine 125 with alternate periods of motion and rest.
130. In a device of the character specified, the combination with the objective, of a carriage having magazines above and below the objective for receiving and distributing the

plates, means for moving the carriage laterally past the objective in opposite directions with alternate periods of movement and rest, and means movable with the carriage for 5 moving the plates vertically past the objective from the lower magazine to the upper magazine with alternate periods of movement and rest.

16. In a device of the character specified, 10 the combination with the carriage having upper and lower magazines for the plates, of means operated by the movement of the plates into the upper magazines for moving the plates in the lower magazines in the opposite direction, said means comprising a double armed lever, the arms being pivotally connected at their meeting ends, and means for securing the arms from movement angularly with respect to each other.

20 17. In a device of the character specified, the combination with the carriage having

upper and lower magazines for the plates, of means operated by the movement of the plates into the upper magazines for moving the plates in the lower magazines in the opposite direction. 25

18. In a device of the character specified, a carriage for supporting the plates, said carriage having upper and lower magazines, means for engaging and moving the individual plates vertically from the lower to the upper carriage with alternate periods of motion and rest, and means in connection with the said means for increasing the extent of movement of the said means at predetermined intervals. 30 35

In witness whereof I have hereunto set my hand in the presence of two witnesses.

RENÉ ACHILLE ROBIN.

Witnesses:

LÉON FRANEKEN,
C. O. WIESEMANN.
